SHEET FEED ROTARY PRINTING PRESS

Howard M. Barber, Pawcatuck, Conn., assignor
to C. B. Cottrell & Sons Company, Westerly,
R. I., a corporation of Delaware

Application April 30, 1932. Serial No. 608,413

14 Claims. (Cl. 101—174)

The object of this invention is to provide means whereby sheets fed from two separate sources of supply may be transferred accurately directly to an impression cylinder having an odd number 5 of impression surfaces, by two transfer devices, each transfer device being arranged to take successive sheets from its particular source of sheet supply and to transfer the sheets directly to alternate surfaces of the impression cylinder; there-
10 by eliminating the handling of the sheets more than once on their way from their source of sheet supply to the impression cylinder.

A practical embodiment of my invention is represented in the accompanying drawings, in
15 which:

Fig. 1 represents a detail side elevation of a sheet feed rotary printing press with my improved sheet feeding mechanism included there-
in;

20 Fig. 2 represents a detail end view of the press with the form cylinders and delivery mechanism removed; and

Fig. 3 represents a longitudinal vertical central section through the press.

25 Five form cylinders 1, 2, 3, 4, 5 are shown arranged around the upper side of their impression cylinder 6. This impression cylinder 6 is herein shown as having three impression surfaces 7, 8, 9 and their three sets of sheet grippers 10,
30 11, 12, the distances between the grippers equaling the circumferences of the form cylinders.

Two sources of sheet supply are herein shown as sheet feed tables 13 and 14 arranged one above the other, on the same side of the impression cylinder, the upper feed table being provided with
35 the sheet stop 15 mounted on its rock shaft 16, and the lower sheet feed table being provided with the sheet stop 17 mounted on its rock shaft 18.

40 Two rotary sheet carriers 19, 20, which are herein shown as reels are arranged to transfer the sheets from their respective upper and lower sheet feed tables 13 and 14 to the impression cylinder 6. The upper rotary sheet carrier is pro-
45 vided with a set of grippers 21 which is arranged to take a sheet every second revolution of the rotary carrier from the sheet feed table 13 and transfer it to the grippers of alternate impres-

50 sion surfaces of the impression cylinder 6. Simi- larly, the lower rotary sheet carrier 20 is provided with a set of grippers 22 which is arranged to take a sheet every second revolution of the carrier from the lower sheet feed table 14 and transfer the sheet to the grippers of alternate impres-

55 sion surfaces of the impression cylinder 6. There-

fore, successive impression cylinder surfaces receive sheets alternately from said two sources of sheet supply.

As the rotary carriers 19 and 20 transfer a sheet at alternate revolutions of the carriers to the impression cylinder it is necessary to provide means to make the sheet stops 15 and 17 and the rotary carrier grippers 21 and 22 inoperative at every other revolution of their respective carriers. It is also necessary to control the 65 operation of the impression cylinder grippers so that each set of grippers 10, 11 and 12 will alternately take sheets from the two rotary sheet carriers.

The means which I have shown for accomplishing this result is constructed, arranged and operated as follows:

The cam shaft 23 for controlling the operation of the sheet stop 15 of the feed table 13 and also for controlling the operation of the grippers 21 75 of the rotary carrier 19 as well as the operation of the grippers 10, 11, 12 of the impression cylinder is driven from the shaft 24 of the rotary carrier 19 through a chain and sprocket connection 25, 26, 27 at one-half the speed of the said rotary carrier 19. This cam shaft 23 is provided with a cam 28 which operates the sheet stop 15 to release the sheet every second revolution of the rotary carrier 19 through the lever 29 carried by the rock shaft 16. A cam 30 on the cam shaft 80 23 serves to control the operation of the tumbler actuating pins 31, 32, to actuate the grippers 21 to take the sheet from the feed table 13 and transfer it to the proper set of impression cylinder grippers, through the rock shaft 33 and its 85 rock levers 34, 35, 36. Another cam 37 on the shaft 23 controls, through a rock lever 38, the lateral movement of the movable member 39 of the impression cylinder gripper cam 39, 40, so that the movable cam member 39 can be moved 90 out of its operative position to permit the passage of the impression cylinder grippers which have taken a sheet from the lower rotary carrier 20.

The cam shaft 41 for controlling the operation of the sheet stop 17 for the lower sheet feed table 14 and also the tumbler actuating grippers 22 of the rotary carrier 20 is driven at half speed from the shaft 42 of the rotary carrier 20 through the chain and sprocket connection 43, 44, 45. This shaft 41 is provided with a cam 46 which operates the sheet stop 17 to release a sheet from the table 14 every second revolution of the rotary carrier 20, through a lever 47 carried by the rock shaft 18. This cam shaft 41 is also provided with a 110

cam 48 which controls the operation of the tumbler cam actuating pins 49, 50 to operate the grippers 22 to take a sheet from the table 14 and transfer it to the proper impression cylinder 5 grippers, through a rock shaft 51 and its levers 52, 53 and 54.

The delivery mechanism is herein shown as including a rotary carrier 55 located at the underside of the impression cylinder 6, which delivery carrier 55 is provided with a set of grippers 56 arranged to take the printed sheets from the successive impression cylinder grippers and transfer the sheets to a suitable endless delivery carrier 57. A cam 58 is located in position to open the delivery carrier grippers 56 to receive the printed sheet from its impression cylinder grippers. Another cam 59 is arranged in position to open the delivery carrier grippers 56 for transferring the printed sheet to the endless delivery carrier 57.

From the above description it will be seen that each sheet transfer carrier operates every second revolution to take a sheet from its sheet feed table and transfer the sheets to alternate surfaces of the impression cylinder so that successive impression surfaces bear sheets from alternate sheet feed tables. It will also be seen that the fixed member 40 of the impression cylinder gripper cam operates to open the impression cylinder grippers successively after the last printing impressions on the sheets to permit the printed sheets to be taken by the delivery carrier and transferred thereby to the endless carrier. It will also be seen that the movable member 39 of the impression cylinder gripper cam is moved out of the way of the set of grippers which is to take a sheet from the lower transfer carrier 20, thereby permitting the grippers to take the said sheet. Said movable cam member is moved into the way of the set of grippers which is to take a sheet from the upper transfer carrier 19, thereby causing said grippers to remain open until in position to take the said sheet.

It will also be seen that by this invention the sheets are transferred from each source of sheet supply directly to the impression cylinder, thus ensuring greater accuracy in register than is possible where, as heretofore, the sheets were taken from one source by a carrier, transferred to another carrier and then transferred by the latter carrier to the impression cylinder.

What I claim is:

1. In a sheet feed rotary printing press, a plurality of form cylinders, an impression cylinder having an odd number of impression surfaces and two sheet transfer devices, each device being arranged to transfer its sheets directly to alternate surfaces of the impression cylinder.

2. In a sheet feed rotary printing press, a plurality of form cylinders, an impression cylinder having three impression surfaces and two sheet transfer devices, each device being arranged to transfer its sheets directly to alternate surfaces of the impression cylinder.

3. In a sheet feed rotary printing press, a plurality of form cylinders, an impression cylinder having an odd number of impression surfaces, two sources of sheet supply and two rotary sheet carriers, each arranged to take sheets from its source and transfer the sheets directly to alternate surfaces of the impression cylinder.

4. In a sheet feed rotary printing press, a plurality of form cylinders, an impression cylinder having three impression surfaces, two sources of sheet supply and two rotary sheet carriers, each

arranged to take sheets from its source and transfer the sheets directly to alternate surfaces of the impression cylinder.

5. In a sheet feed rotary printing press, a plurality of form cylinders, an impression cylinder having an odd number of impression surfaces, two sources of sheet supply and two rotary sheet carriers, each arranged to take sheets from its source every second revolution and transfer the sheets directly to alternate surfaces of the impression cylinder.

6. In a sheet feed rotary printing press, a plurality of form cylinders, an impression cylinder having three impression surfaces, two sources of sheet supply and two rotary sheet carriers, each arranged to take sheets from its source every second revolution and transfer the sheets directly to alternate surfaces of the impression cylinder.

7. In a sheet feed rotary printing press, a plurality of form cylinders, an impression cylinder having an odd number of impression surfaces, two sources of sheet supply and a rotary carrier for each source of sheet supply, each rotary carrier being arranged to take a sheet from its source and transfer the sheet directly to the impression cylinder every second revolution of the carrier.

8. In a sheet feed rotary printing press, a plurality of form cylinders, an impression cylinder having three impression surfaces, two sources of sheet supply and a rotary carrier for each source of sheet supply, each rotary carrier being arranged to take a sheet from its source and transfer the sheet directly to the impression cylinder every second revolution of the carrier.

9. In a sheet feed rotary printing press, a plurality of form cylinders, an impression cylinder having an odd number of impression surfaces, two sources of sheet supply and a rotary carrier for each source of sheet supply, each rotary carrier being arranged to take a sheet from its source and transfer the sheet directly to the impression cylinder every second revolution of the carrier, the two carriers being arranged to transfer sheets alternately to successive surfaces of the impression cylinder.

10. In a sheet feed rotary printing press, a plurality of form cylinders, an impression cylinder having three impression surfaces, two sources of sheet supply and a rotary carrier for each source of sheet supply, each rotary carrier being arranged to take a sheet from its source and transfer the sheet directly to the impression cylinder every second revolution of the carrier, the two carriers being arranged to transfer sheets alternately to successive surfaces of the impression cylinder.

11. In a sheet feed rotary printing press, a plurality of form cylinders, an impression cylinder having an odd number of impression surfaces and their respective sets of sheet grippers, two sheet transfer devices and means for causing a selected set of impression cylinder grippers to take the sheets alternately from said two sheet transfer devices.

12. In a sheet feed rotary printing press, a plurality of form cylinders, an impression cylinder having three impression surfaces and their respective sets of sheet grippers, two sheet transfer devices and means for causing a selected set of impression cylinder grippers to take the sheets alternately from said two sheet transfer devices.

13. In a sheet feed rotary printing press, a plurality of form cylinders, an impression cylinder

having an odd number of impression surfaces and their respective sets of sheet grippers, two rotary sheet carriers and means for causing a selected set of impression cylinder grippers to take the 5 sheets alternately from said two sheet carriers.

14. In a sheet feed rotary printing press, a plurality of form cylinders, an impression cylinder

having three impression surfaces and their respective sets of sheet grippers, two rotary sheet carriers and means for causing a selected set of impression cylinder grippers to take the sheets alternately from said two sheet carriers.
